UNITED STATES PATENT OFFICE.

ALEXANDER C. BOHLIN, OF NEW YORK, N. Y.

ADJUSTABLE AUGER.

No. 796,182.

Specification of Letters Patent.

Patented Aug. 1, 1905.

Application filed January 7, 1905. Serial No. 240,024.

To all whom it may concern:

Be it known that I, ALEXANDER C. BOHLIN, a citizen of the United States of America, and a resident of the borough of Brooklyn, New York city, State of New York, have invented certain new and useful Improvements in Adjustable Augers, of which the following is a specification.

My invention relates to adjustable wood-boring augers; and it consists of the improved construction of such tools hereinafter described, reference being made to the accompanying drawings, in which—

Figure 1 is an elevation of my improved adjustable auger complete, and Fig. 2 is an elevation with a part in vertical section.

A represents the shaft of the tool, having the handle-connecting shank *b* of the upper end and the gimlet-point *c* of the lower end and the short fixed radial boring-bit *d* at the junction of the base of the gimlet-point with the end of the shaft. For the application of the extensible bit *e* I provide a mortise *f* diametrically through the lower end portion *f'* of the shaft just above the junction of the gimlet-point *c*, said end portion of the shaft preferably being a little larger in diameter than the rest of the shaft, above which enlargement is a screw-threaded section *g*, whereon a clamping-nut *h* is threaded for screwing up and down freely, said nut having an expanded socket *i* on the lower side of suitable internal diameter to slip down over end portion *f'* to some extent below the upper portion of mortise *f*, and I construct said expansible bit *e* with a shank *j*, to which said bit is connected near one end by a web *k*, with a parallel space *l* between the rear edge of the bit, enabling said shank to be inserted in the slot, so as to be shifted along from one position to another, with the back edge of the bit bearing against the surface of a flattened portion of part *f'* at *m* for support against the resistance of the work on the bit *e*. The nut *h* is when the

bit is set in the desired position readily screwed down onto shank *j* to bind it fast.

It will be seen that the shaft is much stronger with the slot for reception of the shank of the bit *e* than when a notch is made in the side of the shaft, which necessitates cutting away considerably more than one-half of the metal, and the clamping-nut affords the means, by the flat-sided part *m'*, for the use of a wrench in tightening it, by which it can be tightened more securely than can be effected with a set-screw operated by a screw-driver in the common way.

What I claim as my invention is—

1. In an extensible auger, the combination with the shaft having a transverse slot above and in proximity to the gimlet-point, of the adjustable bit having the shank traversing said slot and the cutting portion connected with the shank by a web leaving a clearance-space between the shank and cutting portion permitting lateral adjustment of the bit, and the clamping-nut on the shaft above the bit-shank adapted to clamp said shank for securing the bit, substantially as shown and described.

2. In an adjustable auger, the combination with the shaft having a transverse slot above and in proximity to the gimlet-point, of the adjustable bit having the shank traversing said slot with a clearance-space between said shank and the cutting portion of the bit permitting lateral adjustment of the bit, and the clamping-nut on the shaft above the bit-shank and adapted to clamp said shank for securing the bit, said cutting portion of the bit having bearing-contact of the rear edge with the side of the shaft.

Signed at New York this 27th day of December, 1904.

ALEXANDER C. BOHLIN.
